United States Patent Office.

EPHRAIM P. ROGERS, OF CORNING, NEW YORK, ASSIGNOR TO HIMSELF,
R. W. PAYNE, AND HIRAM PRITCHARD, OF SAME PLACE.

Letters Patent No. 74,852, dated February 25, 1868.

IMPROVEMENT IN GOVERNORS.

The Schedule referred to in these Letters Patent and making part of the same.

TO ALL WHOM IT MAY CONCERN:

Be it known that I, EPHRAIM P. ROGERS, of Corning, in the county of Steuben, and State of New York, have invented a new and improved Governor; and I do hereby declare that the following is a full, clear, and exact description thereof, which will enable those skilled in the art to make and use the same; reference being had to the accompanying drawings, forming part of this specification.

This invention relates to a new and improved construction of governors, for steam-engines and other purposes, whereby the same are rendered more effective in their operation, and whereby the expense or cost is materially lessened; and the invention consists in the construction and arrangement of parts, as hereinafter described.

Figure 1 represents a vertical section of the governor through the line $z z$ of fig. 2, showing the parts of which it is composed in their proper positions.

Figure 2 is a vertical elevation of the same, showing the form of the hollow disk.

Similar letters of reference indicate corresponding parts.

This governor is the kind known as the centrifugal or pendulum-governor, but in this case the centrifugal force of the balls is resisted by a weight, through the medium of a transverse bar and connecting-links. A spring instead of a weight may be used, if desired, for controlling or modifying the action of the balls.

A represents a hollow disk, which is cast with the hollow or tubular stem B. C is the spindle, which is connected with the governor-valve at its lower end, and receives its longitudinal motion through the action of the balls. D represents the balls. E represents the arms of the balls. F is a transverse bar, to which the spindle C is connected, by a swivel-joint, f, as seen in the drawing. G represents links, which connect the bar with the arms E of the balls D. These arms are in fact levers, whose fulcra are at $h h$. The governor is revolved by bevel-gearing, seen in the drawing in red, and marked J J. K represents a weight, the stem of which, m, passes down through the neck n of the disk A, and rests on the middle of the bar F. It will be seen that when the governor is in motion, and the balls are raised by the centrifugal force, the action will be communicated to the transverse bar F and the weight K, and that this action cannot commence until the necessary speed is given to the governor. This resistance to the rising of the balls is made above the fulcra h , or point of suspension of the balls. A spring, or a spring and weight combined, may be used in this connection, for acquiring the necessary speed in the governor above the point of suspension. o represents an opening in the hollow disk A, for the purpose of more easily adjusting the connection at f. P P represent slots in the edge of the disk A, in which the arms of the balls play. By this construction much valuable time and labor are saved, and consequently the expense of the governor is lessened.

What I claim as new, and desire to secure by Letters Patent, is—

The governor, constructed as described, and consisting of the hollow slotted disk A, having tubular stem B and neck n, the weight K provided with stem m, valve-stem C, swivel-joint f; cross-bar F, connections G, levers E and balls D, all arranged and operating as set forth.

EPHRAIM P. ROGERS.
